CLAIM

The ornamental design for a cymbal mount fitting, as shown.

DESCRIPTION

FIG. 1 is a perspective view from the top and side of a cymbal mount fitting, showing my new design;

FIG. 2 is another perspective view from the bottom and side thereof;

FIG. 3 is a side elevational view thereof; and,

FIG. 4 is a top plan view thereof.

FIG. 1

FIG. 2

FIG. 3

FIG. 4
